A. D. GROVER,
HEAD TIGHTENING DEVICE FOR BANJOS AND THE LIKE,
APPLICATION FILED MAY 16, 1919.

1,338,076.

Patented Apr. 27, 1920.

UNITED STATES PATENT OFFICE.

ALBERT D. GROVER, OF NEW YORK, N. Y.

HEAD-TIGHTENING DEVICE FOR BANJOS AND THE LIKE.

1,338,076.

Specification of Letters Patent. Patented Apr. 27, 1920.

Application filed May 16, 1919. Serial No. 297,465.

To all whom it may concern:

Be it known that I, ALBERT D. GROVER, a citizen of the United States, and a resident of New York city, in the county of New York and State of New York, have invented 5 certain new and useful Improvements in Head-Tightening Devices for Banjos and the like, of which the following is a specification.

10 My invention relates generally to musical stringed instruments, such as the banjo and others of that type, and its object is to provide a readily attachable device for keeping the parchment head of the instrument in tight condition.

15 It is well understood by players of the banjo that the instrument is not in good playing condition unless the head is tight. In damp weather the head becomes loose 20 and flabby, thus making the instrument unfit for playing—at least, the tone produced under such conditions is dull and does not carry far. In the parlance of the players, the banjo becomes “dead.” Heretofore the 25 player would tighten the head of his instrument by turning down the bracket screws. But it was found that this pulling-down process was ruinous to the head. If the bracket screws were not loosened in 30 time, the head would on the next dry day break or crack owing to the contraction.

35 A form of head-tightening device heretofore used consisted of a wire ring pressed against the inside of the head to push the same outwardly. But these “tone rings,” as they are usually called by the players, are objectionable for various reasons. For instance, the inevitable effect of such a ring is to decrease the effective diameter of the 40 head. In other words, it makes a smaller banjo out of a larger one and consequently the volume of sound is decreased. Another serious objection to the use of those wire rings is that they push the head up against 45 the extension of the finger board and at the same time raise the bridge, so that the strings are being constantly forced away from the finger board. Furthermore, when a player wants to place one of those “tone 50 rings” on his banjo, the instrument has to be sent to the shop and taken apart in order to get the ring in under the head.

55 The foregoing objections are entirely obviated by my new head-tightening device, which is simple in construction and can be

instantly attached to any banjo. The objects and advantages of my device will become apparent from a detailed description of a preferred embodiment thereof, as shown in the accompanying drawings, in 60 which—

Figure 1 shows the back of a banjo with my new head-tightening device in place;

Fig. 2 is a cross-section on line 2—2 of Fig. 1;

Fig. 3 is a cross-section on line 3—3 of Fig. 1;

Fig. 4 is an enlarged detailed view in cross-section, approximately on line 4—4 of Fig. 1; and

Fig. 5 is a perspective view (partly broken away) of one of the contact members which bear against the head.

Since the banjo to which my device is shown attached is of the usual construction, 75 it will not be necessary to describe the details thereof, and I will only say that 1 represents the head, 2 the stick, 3 the bracket screws, and 4 a portion of the finger board. In Fig. 1, the dotted lines 5 indicate the 80 tail piece, 6 the bridge, and 7 the strings.

My new head-tightening device comprises a pair of separated contact pieces A and a support for holding them pressed against the inner side of the head. In the broader 85 aspect of my invention, this support may be mechanically embodied in various forms, but at present I prefer a bar B, which is stiff and of suitable resilient material. The contact pieces A are preferably, but not 90 necessarily, substantially arc-shaped. I have obtained highly satisfactory results by making the contact members and the bar of metal, such as steel, although other resilient material may be used. The bar may 95 be made stiff and yet light by providing the same with side flanges 8. To establish an easily separable and adjustable connection between the bar B and the contact pieces A, I provide the latter with a tongue or projection 9 adapted to enter between the side flanges 8 of the bar. This is best shown in Fig. 4.

The bar B is attached to the stick 2 of the instrument by any suitable means, but I 105 prefer to use the attaching plate shown in the drawings. This attaching plate is the same as that shown and claimed in my co-pending application Serial No. 145,572, filed January 31, 1917. Briefly described, this 110

attaching plate comprises a metal base plate 10 provided with a pair of fixed pins 11 which project through a pair of alined openings formed in the bar B. The base 5 plate 10 is also provided with a pair of pointed screws 12 which bite into the wood of the stick 2 and thereby firmly hold the plate 10 and the bar B against turning movement relatively to the stick. A pair 10 of thumb screws 12, also carried by the plate 10, allow the player to readily adjust the pressure of the contact pieces A against the head.

It will be clear from the foregoing that I 15 have provided an exceedingly simple and efficient device for keeping the head of the banjo, or like instrument, in tight condition. The device is very easily attached, since the contact pieces A and the bar B are 20 separable. The slideable engagement between the bar B and the contact pieces A permits the use of the device on different-sized banjos, or allows the player to place the contact pieces at the desired distance 25 from the rim. Referring to Fig. 1, the contact pieces A are shown in full lines in what I should regard as their best position for the size of banjo illustrated. If the device is applied to a larger banjo, the contact 30 pieces may be moved outwardly into the dotted-line position A'. Should conditions require, the contact pieces may be moved inwardly into the position roughly outlined by the dotted lines A².

35 The head-tightening device may be left on the banjo as a permanent attachment. It does not perceptibly add to the weight of the instrument and is never in the way. In dry weather the thumb screws 13 are so adjusted 40 that the contact pieces A exert but a slight pressure on the head under the influence of the resilient bar B. Should the player find that the head of his banjo is becoming loose or flabby, he simply tightens the screws 13 45 until he finds that the pressure against the head is sufficient to take up the slackness. This manipulation of the thumb screws 13 is but the work of a few moments, and may in fact be done during the playing of a selection, should the occasion require it.

When I refer to the contact pieces A as being substantially arc-shaped, I do not mean to imply any limitation as to their precise configuration. I simply mean that the 55 contact pieces should in a rough and general way follow the curvature of the rim, whereby the pressure against the head is more or less evenly distributed. The precise location of the contact pieces is immaterial, provided 60 that the lines or places of contact are away from the string-supporting bridge 6. If the contact pieces extended under bridge 6, or in close proximity thereto, or in the space between the bridge and the tailpiece (as is the 65 case with the so-called "tone rings" previ-

ously referred to), the result would be a dulled or muted tone, instead of the sharpened, increased tone caused by my device.

Having thus described my invention, what I claim as new and desire to secure by Letters Patent of the United States, is:

1. In combination with a banjo or the like, a stiff bar connected at or near its center with the stick of the instrument, and separated curved contact members supported 75 on the bar between the free ends of said bar and the head, said members bearing against the inner side of the head to exert an outward pressure thereon under the influence of said bar and thereby maintain the head taut. 80

2. In combination with a banjo or the like, a stiff bar connected at or near its center with the stick of the instrument, separated curved contact members supported on the bar between the free ends of said bar 85 and the head, said members bearing against the inner side of the head to exert an outward pressure thereon under the influence of said bar and thereby maintain the head taut, and readily operable means for adjusting 90 the pressure of said members against the head.

3. In combination with a banjo or the like, a stiff bar connected with the stick of the instrument, and contact members slidably connected with the free ends of said bar and located between the bar and the head, said members bearing against the inner side 95 of the head to exert an outward pressure thereon under the influence of said bar and thereby maintain the head taut. 100

4. In combination with a banjo or the like, a metal bar connected at or near its center with the stick of the instrument, and substantially arc-shaped contact members of 105 metal supported on the bar between the free ends of said bar and the head, said members bearing against the inner side of the head to exert an outward pressure thereon under the influence of said bar and thereby maintain 110 the head taut.

5. In combination with a banjo or the like, a bar connected at or near its center with the stick of the instrument, said bar having side flanges to stiffen it, and a pair 115 of substantially arc-shaped contact members adjustably connected with the ends of said bar and arranged between the bar and the head, said members bearing against the inner side of the head to exert an outward pressure thereon under the influence of said bar and thereby maintain the head taut. 120

6. In combination with a banjo or the like, a bar connected at or near its center with the stick of the instrument, said bar having side flanges to stiffen it, a pair of substantially arc-shaped contact members adjustably connected with the ends of said bar and arranged between the bar and the head, said members bearing against the 125 130

inner side of the head to exert an outward pressure thereon under the influence of said bar and thereby maintain the head taut, and means for adjusting said bar at its middle

5 section toward and away from the head to vary the pressure of said members against the head.

7. In combination with a banjo or the like, a bar connected at or near its center 10 with the stick of the instrument, said bar having side flanges to stiffen it, and a pair of substantially arc-shaped contact members connected with the ends of said bar and arranged between the bar and the head, said 15 members having each a tongue or projection arranged to engage the bar between said flanges, whereby said members are slidable on said bar, said members bearing against the inner side of the head to exert an outward pressure thereon under the influence of 20 said bar and thereby maintain the head taut.

8. In combination with a banjo or the like, a pair of separated substantially arc-shaped contact members bearing against the 25 inner side of the head, and a support for holding said members pressed against the head to keep the same taut.

9. In combination with a banjo or the like, a pair of separated substantially arc-shaped contact members bearing against the 30 inner side of the head, a support for holding

said members pressed against the head to keep the same taut, and means for adjusting said support to vary the pressure of said members against the head.

35

10. A head-tightening device for banjos and the like, comprising a stiff bar to be connected at or near its center with the stick of the instrument, and a pair of separated substantially arc-shaped contact members 40 adapted to be adjustably connected with the free ends of said bar to bear against the inner side of the head.

11. A head-tightening device for banjos and the like, comprising a stiff bar adapted 45 to be connected at or near its center with the stick of the instrument, and a pair of contact members adapted to be connected with the free ends of said bar to bear against the inner side of the head, each of said members 50 having a tongue or projection for slidable engagement with said bar.

12. In combination with a banjo or the like, a pair of separated substantially arc-shaped contact members bearing against the 55 inner side of the head, and a support for holding said members pressed against the head to keep the same taut, said members being adjustably connected with said support.

In witness whereof, I hereunto subscribe 60 my name this 15th day of May, 1919.

ALBERT D. GROVER.
